UNITED STATES PATENT OFFICE.

JAMES A. LANSING, OF SCRANTON, PENNSYLVANIA, ASSIGNOR TO SCRANTON STOVE WORKS, OF SCRANTON, PENNSYLVANIA, A CORPORATION OF PENNSYLVANIA.

RANGE.

1,153,322.

Specification of Letters Patent. Patented Sept. 14, 1915.

Application filed December 23, 1914. Serial No. 878,784.

To all whom it may concern:

Be it known that I, JAMES A. LANSING, a citizen of the United States, residing at Scranton, in the county of Lackawanna and State of Pennsylvania, have invented certain new and useful Improvements in Ranges; and I do hereby declare the following to be a full, clear, and exact description of the same, reference being had to the accompanying drawings, forming part of this specification, and to the figures and letters of reference marked thereon.

This invention relates to improvements in domestic ranges, particularly of the type disclosed in my prior Patent No. 1,021,640, granted December 22, 1914.

In ranges of the type therein disclosed, the ordinary open gaseous fuel burners and oven are supplemented by a firebox adapted for the consumption of any variety of solid fuel. Exposed to the combustion chamber on one side is a water back, a second combustion chamber in which gaseous fuel burners are arranged being provided on the other side of the water back, so that water in a single reservoir can be heated by either gaseous or solid fuel.

The object of the present improvement is to provide a construction permitting the utilization of coils in which the water can be heated by the consumption of either solid or gaseous fuel, or both.

In practice it has been found that coils are very much more satisfactory for heating water than the ordinary water back, because a much larger area of water is brought under the influence of the heat, and the opportunity offered for circulation of the water through the coils permits a very rapid absorption of heat, bringing the water in the boiler to the required temperature with greater rapidity than can be obtained by the use of the ordinary water back. In my improved construction the coils are so arranged within the stove that they may very readily be removed bodily from the stove by simply removing one of the outside panels.

A full understanding of the nature and objects of the invention will be attained from the following detail description taken in connection with the accompanying drawings, illustrating a construction embodying the invention in a preferred form and the novel features thereof pointed out in the appended claims.

In the drawings, Figure 1 is a longitudinal section of a range made in accordance with the present invention; Fig. 2 is a top plan view of the combustion chambers with certain of the parts shown in section; Fig. 3 is a transverse section on the line 3-3 of Fig. 1; Fig. 4 is a fragmentary section on the line 4-4 of Fig. 3; and Fig. 5 is a fragmentary longitudinal section of a range having a modified form of construction.

Referring more particularly to the drawings, in which similar characters of reference indicate similar parts throughout the several views, the oven portion of the range, indicated generally by the letter A, is adapted to be heated by gaseous fuel burners A', and it may also be provided with a broiler burner A² located at or near the top of the oven. In the space B above the oven are arranged the usual open burners B' B², these being assembled, in a manner well known in the art, beneath a grate top C of ordinary construction.

The products of combustion flow from the oven burner A' into a flue box D, through an opening D' at the back of the range. The draft may be controlled by a suitable plate damper D² mounted on an operating rod D³ which extends transversely across the range and through the front panel to permit it to be grasped by the hand. To insure a slight draft, even when closed, the damper plate D² is preferably perforated. Such a construction is particularly desirable in gas ranges, since it insures the passing off of poisonous gases under all conditions. The flue box is located at the back of the range directly beneath a flue E through which the products of combustion pass into the atmosphere.

Located at one side of the oven is a fire box F adapted for the consumption of solid fuel. This fire box embodies the usual combustion chamber and has three of its sides lined with fire bricks F'. The fuel is supported by grate bars F² located in the lower portion of the fire box. In the form of the invention shown in Figs. 1 to 4, inclusive, the fire box F is separated from the oven A and open burners B by a vertical partition G, this partition being provided with a deflecting plate G' located on the side of the fire box and extending beneath the grate bars F² for directing the ashes and clinkers into an ashpit H beneath the fire box. On the opposite side of the fire box from the

oven A, is a combustion chamber K for the burning of gaseous fuel. This chamber is separated entirely from the fire box by a partition I to prevent dust and clinkers from finding their way into the same. On its outer side the combustion chamber is closed by the outer wall of the range which is conveniently a hollow door K' having slide control dampers, preferably upper and lower 5 dampers K² K³, which provide a means for controlling the supply of air admitted to the chamber K through the inner door opening K⁴. A series of openings K⁵ in the wall K⁶ permits air to flow into the combustion 10 chamber at all times.

Within the combustion chamber K, is a series of gaseous fuel burners L. These burners are preferably made long enough to extend transversely across the range through 15 the chamber K, and are arranged in spaced superposed relation. The burners may be conveniently supported at their outer ends in a removable front plate or door K⁷, and at their inner ends upon spaced brackets K⁸ 20 secured to the back wall of the combustion chamber K. Gaseous fuel is supplied to all the burners by a manifold L' and the amount of heat within the combustion chamber can be conveniently regulated by providing each burner with a suitable cut off valve L². The manifold L' is provided with a coupling L³ connecting it to the main pipe line. This arrangement of the burners enables them to be removed bodily from the 25 combustion chamber by simply unscrewing the coupling member L³ and removing the front plate K⁷. The invention provides means for heating water either by the burners L or the combustion of solid fuel in the 30 fire box F. In the present improvements this is attained by the use of a heating coil extending into both the gas burner chamber and the fire box. The pipe M leading from a suitable domestic boiler, not shown, enters 35 the chamber K preferably from the rear and extends directly above the lowermost burner L throughout practically its entire extent to the front of the chamber K, whence it passes through a slot I' in the partition I into the firebox. In the fire box the 40 pipe M extends transversely of the stove to the rear and back again forming a coil M², which again passes into the combustion chamber K through the second slot I², the 45 continuation M³ of the coil extending directly above the second burner L and coiling back over and throughout the extent of the third burner L, whence it again passes 50 through the slot I³ into the fire box, forming 55 therein a second coil M⁴ arranged above the coil M². The coil M⁴ passes through the partition I back into the combustion chamber K through which it extends, and passes 60 out of the chamber at the rear and back to 65 the boiler. Suitable pipe couplings M⁵ M⁶

are provided which, when unscrewed, permit the entire arrangement of coils to be removed bodily from the stove when the plate K⁷ is removed. This construction will be found very advantageous, for it permits a ready detachment of the coils from the stove 70 for cleaning purposes.

In operation the water circulates from the boiler through the coils alternately back and forth into the two chambers. In this way heating of the water may be obtained either by the consumption of gaseous fuel in the combustion chamber K or the burning of solid fuel in the fire box F. The above arrangement will be found very useful in 80 heating water when there is no fire in the fire box, since by lighting the burners L the water circulating through the coils can be very quickly heated. Under ordinary conditions, when there is a fire in the fire box 85 F, it will not be found necessary to employ the gas burner L for heating the water, the coils within the firebox being sufficient for this purpose. They will be found very useful, however, in quickly heating the water 90 just after a fire has been lighted in the fire box, the combined heat of the two combustion chambers being great enough to heat all the water in the boiler in a comparatively short space of time. When the water 95 in the boiler is brought to a sufficiently high temperature, the gas burners may be extinguished and the heat in the fire box will be found quite sufficient to keep the water hot.

The present arrangement will be found to 100 be of great value in domestic ranges, especially in modern kitchens, where there is ordinarily not very much space, since it combines in a single unitary construction all the advantages of a coal range and a gas 105 water heater.

In the exceedingly small kitchens of today the improved range will be found very valuable since it does not take up any more space than a range of ordinary construction. 110 At times, it will be found desirable to direct the heat and products of combustion from the chamber K into the fire box F, for instance, when incinerating garbage, or at other times, when a large quantity of heat 115 is desired. For this purpose, the partition I is provided with a plate damper N located near the top and controlled by a damper rod N'. When the damper N is open, the heat from the chamber K passes directly 120 into the upper portion of the fire box F. Under normal conditions, the products of combustion from the chamber K pass through an opening O located at the rear, into the flue box D. The draft may be controlled by a plate damper O', operated by a rod O².

In Fig. 5 I have shown a modification. The gas burner chamber K is located between the oven A and the fire-box F; the 130

pipe M enters the chamber from the rear and passes in like manner back and forth between the chamber and fire box forming similar heating pipes M' above the gas 5 burner L and vertical coils M² along the partition P. The flow of the products of combustion is similarly controlled by dampers N and O. To support combustion within the chamber K air is admitted through 10 air openings R.

While I have shown and described a certain specific embodiment of my invention, it will be understood that the same is not to be limited to the details of construction, 15 but on the contrary is capable of modification and variation within the scope of the claims.

What is claimed is:

1. In a range, the combination of a fire 20 box for the consumption of solid fuel, a gaseous fuel chamber with gaseous fuel burners in said chamber, a partition separating the fire box from the gaseous fuel chamber, and a continuous water circulating medium 25 having coils extending directly over the burners in the gaseous fuel chamber and coils in the fire box lying against the separating partition whereby water may be heated by the combustion of fuel in both the 30 fire box and the gaseous fuel chamber.

2. In a range, the combination of a fire 35 box for the consumption of solid fuel, a gaseous fuel chamber with gaseous fuel burners in said chamber, a partition separating the fire box from the gaseous fuel chamber, and a continuous water circulating coil 40 extending alternately back and forth from

the gaseous fuel chamber into the fire box, the coils in the gaseous fuel chamber lying directly above the burners, and the coils in 45 the fire box lying against the separating partition, whereby water may be heated by the combustion of fuel in both the fire box and the gaseous fuel chamber.

3. In a range, the combination of a fire 50 box for the consumption of solid fuel, a gaseous fuel chamber with a plurality of superposed elongated gaseous fuel burners in said chamber, a vertical partition separating the fire box from the gaseous fuel chamber, and a continuous water circulating medium having vertically arranged coils extending directly above the respective burners in the gaseous fuel chamber and vertically arranged coils in the fire box lying against the 55 separating partition, whereby water may be heated by the combustion of fuel in both the fire box and the gaseous fuel chamber.

4. In a range, the combination with a fire 60 box for the consumption of solid fuel, a gas burner chamber located at one side of the fire box, a plurality of superimposed burners in said chamber, a removable plate partly supporting said burners, a water coil extending alternately from one combustion 65 chamber into the other, and means for permitting said water coil and burners to be removed bodily from the range by removing said plate.
